[57] CLAIM

The ornamental design for a cabinet or similar article, as shown and described.

DESCRIPTION

FIG. 1 is a view in front elevation of a cabinet or similar article showing my design.

FIG. 2 shows an elevation of the rear of the cabinet; FIG. 3 shows an elevation of the left side of the cabinet; the right side thereof being of corresponding appearance;

FIG. 4 shows a plan view of the cabinet; and

FIG. 5 shows a perspective view of the cabinet.
